CLAIM

The ornamental design for a coffee machine, as shown and
described.

DESCRIPTION

FIG. 1 is a front perspective view of the coffee machine;
FIG. 2 is another front perspective view thereof;
FIG. 3 is a bottom perspective view thereof;
FIG. 4 is a front view thereof;
FIG. 5 is a rear view thereof;
FIG. 6 is a left side view thereof;
FIG. 7 is a right side view thereof;
FIG. 8 is a top view thereof; and,
FIG. 9 is a bottom view thereof.

In some implementations, the coffee machine, as shown in
FIGS. 1, 3, and 6, includes an indentation, on a side,
configured to support a coffee machine tool (e.g., spoon). In
some implementations, as shown in FIGS. 1, 2, and 4, a front
top side of the coffee machine includes a control panel. In
some implementations, the coffee machine, as shown in
FIGS. 1-9, includes handles to access interior portions of the
coffee machine.

The broken lines shown in the figures show features of the
coffee machine that form no part of the claimed design.
